WINDING APPARATUS

Everett P. Larsh, Montgomery County, Ohio
(124 E. Monument Ave., Dayton 2, Ohio)
Filed Sept. 23, 1960, Ser. No. 57,997
10 Claims. (Cl. 242—1.1)

This invention relates to winding apparatus. The invention relates more particularly to winding apparatus for the winding of elements of an electrical machine. The invention relates more particularly to apparatus for winding stators and rotors of electrical machines. The invention relates still more particularly to the winding and forming of coils in stators and rotors. However, the invention is not so limited in that it may be employed for various types of winding operations.

This application relates to my copending applications Serial Number 702,108, filed December 11, 1957, now Patent Number 2,969,928, and Serial Number 19,692, filed April 4, 1960. This application also relates to copending application Serial No. 712,786, now Patent No. 2,954,177, in which the applicant herein is a co-inventor and in which all rights are assigned to the applicant herein.

Electrical elements such as stators and rotors are conventionally wound by the placing of preformed coils in slots of the electrical elements.

A preferable method of winding a stator or a rotor is that in which wires are placed into the slots of the rotor or stator in a manner to form coils in the stator or rotor. In order for such a winding operation to be carried out, it is desirable to use a winding apparatus. The winding apparatus must have a winding element which is capable of laying successive portions of a wire into a slot and then extending the wire from the end of the slot laterally to another slot and then into said other slot so that a coil or coils are formed in the electrical element. In order for the winding element to carry the successive portions of the wire members into and out of the slots of the stator or rotor, reciprocal axial and rotary movement must be provided between the winding element and the element being wound. It is extremely important that the reciprocal axial and rotary movements be very accurately associated and interrelated. This is due to the fact that the rotary and reciprocal movements must occur at the proper relative positions of the winding element and electrical element to accurately place the coils in the proper slots and to form the end turns between the slots.

An object of this invention is to provide means by which an electrical element can be wound accurately and efficiently by placing wires into the coil slots thereof.

Another object of this invention is to provide winding apparatus in which the relative relationships between rotary and reciprocal movements of a winding element are extremely accurately controlled.

Another object of this invention is to provide such winding apparatus in which the relative reciprocal axial and rotary movements of the winding element can be easily and readily adjusted.

Another object of this invention is to provide automatically operable winding apparatus.

Another object of this invention is to provide such winding apparatus which can be manufactured at relatively low costs, may be sturdily built, and is long lived.

Another object of this invention is to provide such winding apparatus which may be easily and readily adjusted for the winding of stators and rotors of various diameters and various axial lengths.

Other objects and advantages reside in the construction of parts, the combination thereof, the method of manu-

2

facture, and the mode of operation, as will become more apparent from the following description.

In the drawings:

FIGURE 1 is an elevational view of the winding apparatus of this invention, with parts broken away and shown in section.

FIGURE 2 is a fragmentary elevational view showing a portion of the apparatus of FIGURE 1 in a position of operation.

FIGURE 3 is an enlarged sectional view taken substantially on line 3—3 of FIGURE 1.

FIGURE 4 is a sectional view taken substantially on line 4—4 of FIGURE 1.

FIGURE 5 is a sectional view taken substantially on line 5—5 of FIGURE 1.

FIGURE 6 is an enlarged sectional view taken substantially on line 6—6 of FIGURE 1.

FIGURE 7 is a diagrammatic sectional view taken substantially on line 7—7 of FIGURE 6.

FIGURE 8 is a diagrammatic type of view, on a reduced scale of elements shown in FIGURE 7, showing another position of operation thereof.

FIGURE 9 is a view taken substantially on line 9—9 of FIGURE 1.

FIGURE 10 is an enlarged sectional view showing the winding head of the winding apparatus of this invention and a wound element in the process of removal therefrom.

FIGURE 11 is a diagrammatic view of the apparatus shown in FIGURE 6 in a position of operation thereof.

FIGURE 12 is a diagrammatic type of view showing the apparatus of FIGURES 6 and 11 in another position of operation thereof.

FIGURE 13 is an enlarged fragmentary perspective view showing a portion of the reciprocal rotary mechanism of the winding apparatus of this invention.

FIGURE 14 is an exploded perspective view showing portions of the winding apparatus of this invention.

Referring to the drawings in detail, winding apparatus of this invention may include any suitable support structure having a base 20 upon which are mounted a plurality of legs, such as leg members 22 and 24, shown in FIGURES 1 and 14. Mounted upon the legs 22 and 24 is a floor structure 26. Rising substantially vertically upwardly from the floor structure 26 is a main wall member 28. Attached to the wall member 28, substantially normal thereto, is a cylindrical housing 30, best shown in FIGURE 14. The cylindrical housing 30 extends through the main wall 28 and has a back wall 32 which is substantially parallel to the main wall member 28, as shown in FIGURE 4. At the end of the cylindrical housing 30 opposite the wall 32 is an opening 33 encompassed by a flange 34, as shown in FIGURE 4.

Attached to the back wall 32 of the cylindrical housing 30 by any suitable means, such as by bolt members 36 and spacer members 38, is a rotary motor 40 provided with a splined shaft 42, as shown in FIGURES 4 and 5. The splined shaft 42 extends through an opening in the back wall 32 and into the housing 30. The splined shaft 42 has attached thereto and carried thereby an eccentric cam member 44 and an eccentric cam member 46. Preferably, the cam members 44 and 46 are rigidly attached one to the other. The cam members 44 and 46 are out of phase, one with respect to the other, as best shown in FIGURE 14. A circular splined connector plate 48 is shown attached to the cams 46 and mounted on the splined shaft 42.

Adjacent the cam member 44 and pivotally carried by a pin 50, which is mounted in the back wall 32, is a cam follower 52. The cam follower 52 is annular and encompasses the splined shaft 42. The cam follower 52 is

provided with a pair of diametrically opposed rollers 54 which are in engagement with the surface of the cam 44. Thus, with each revolution of the cam 44, the cam follower 52 oscillates or swings through one cycle.

5 Adjacent the cam member 46 and pivotally supported adjacent one end portion thereof by a pivot pin 58 is an annular cam follower 60. The cam follower 60 is provided with a pair of diametrically opposed rollers 62 which are in engagement with the peripheral surface of the cam member 46.

Rigidly attached to the cam follower 52 is an arm 64 which extends downwardly therefrom through an elongate opening 66 in the lower portion of the cylindrical housing 30. A lower end portion 68 of the arm 64 is shown as being bifurcated and engages a pin 70 which is connected to a slide tube 72, as shown in FIGURES 6, 11 and 12. The tube 72 slides upon a slide rod 74 which is supported by wall members 76 which extend from the main wall 28 substantially normal thereto.

10 A yoke 78 has end portions 80 which also slidably encompass the slide rod 74. Encircling the slide rod 74 and disposed at opposite ends of the tube 72 are spring members 82 which are compressed between the end portions 80 of the yoke 78 and the tube 72. As shown in FIGURES 4 and 13, the yoke 78 has a connector portion 84 which, with the yoke 78, is slidably carried by upper and lower track surfaces in a wall member 86. The arm 64 extends through a slot 88 in a plate 89 which is attached to the wall member 86.

15 Attached to the connector portion 84 is one or more abutment members 87. These abutment members 87 extend into an irregularly shaped recess 90 of a cam wheel 92, as shown in FIGURES 7 and 8. The cam wheel 92 is supported by a shaft 93 which is rotatably mounted upon a bracket 96, as best shown in FIGURES 4, 6, and 14. The outer periphery of the cam wheel 92 is provided with teeth 94 which are in meshed relation with a pinion 97 carried by a rotary adjustment motor or stepping motor 100. The adjustment motor or stepping motor 100 is ordinarily rotated only a portion of a revolution upon each actuation thereof. Rotary movement of the stepping motor 100 rotates the pinion 97, causing rotary movement of the cam wheel 92. The irregular internal recess 90 of the cam wheel 92 is best shown in FIGURES 7 and 8 and has minimum spaced abutment portions 101, and maximum spaced abutment portions 102. The other abutment portions of the irregular recess 90 are intermediate the portions 101 and 102. The irregular internal recess 90 of the cam wheel 92 limits movement of the abutment members 87 carried by the yoke 78.

20 The connector portion 84 is connected to a chain 103, as best shown in FIGURE 13. The chain 103 encompasses a sprocket wheel 104 having a hub 105 which is splined to a main operating shaft 106, as best shown in FIGURE 6. The main operating shaft 106 extends through a large arcuate notch 107 in the floor 26, as best shown in FIGURE 14. The main operating shaft 106 is slidably axially movable with respect to the hub 105 and the sprocket wheel 104. The hub 105 is held against axial movement with the shaft 106 by spaced-apart horizontal plate members 110 and 111, as shown in FIGURES 1, 2, and 6. The plate member 110 is directly above the hub 105 and the plate member 111 is directly below the hub 105. Any suitable bearing means, not shown, is used between the hub 105 and the plate members 110 and 111. The plate member 111 is a portion of a bracket 112. The upper plate 110 and the lower plate 111 are separated by spacer sleeves 114 through which extend long post members 115. Nut members 116 are attached to the post members 115 directly above and below the plates 110 and 111. The post members 115 also extend through an upper bracket 117 and are secured thereto by nuts 118.

25 The chain 103 is in meshed relation with the sprocket

wheel 104 and is also in meshed relation with an idler sprocket 119 having a hub 121 rotatably carried by a shaft 123.

30 Rotary reciprocal movement of the shaft 106 is carried out by oscillatory movement of the arm 64 which is attached to the cam follower 52. As described above, the cam follower 52 oscillates with rotation of the cam 44. The amount of rotary reciprocal movement of the main operating shaft 106 is governed by the rotary position of the cam member 92. The arm member 64, oscillating with the cam follower 52, always moves the same length of stroke with rotation of its driving cam member 44. However, due to the fact that the arm member 64 is connected to the yoke 78 by means of the spring members 82, the yoke 78 moves only the distance permitted by the internal surface of the rotary cam 92.

35 FIGURE 7 shows the minimum amount of stroke of the yoke 78 permitted. The abutment members 87 are horizontally moved with the movement of the yoke 78 between the portions 101 of the irregular recess 90 of the rotary cam 92. The abutment members 87 engage the abutment surface portions 101 so that the stroke of the yoke 78 is equal to the distance between the wall portions 101 and the spring members 82 absorb the remainder of the stroke of the arm 64 which is greater than any movement of the yoke 78. FIGURE 8 shows the adjusted position of the rotary cam 92 in which movement of the yoke 78 is greatest and is equal to the distance between wall portions 102 of the recess 90.

40 The yoke 78 moves the chain 103 which rotatively moves the main operating shaft 106. Thus, it is understood that the amount of reciprocal rotative movement of the shaft 106 is governed by the adjusted position of the rotary cam 92. As stated above, the rotary position of the cam 92 is adjusted by the stepping motor 100. Thus, the stepping motor 100 is operated only when it is desired to change the amount of rotary reciprocal movement of the main operating shaft 106. The amount of rotary reciprocal movement of the main operating shaft 106 is changed only when it is desired to change the width of the coils or the spacing between sides of coils wound by the apparatus.

45 The cam follower 60, as discussed above, follows rotary movement of the cam 46. The cam follower 60 has integrally attached thereto an arm 120, as shown in FIGURES 1 and 14. The arm 120 extends through an elongate slot 125 in the side of the cylindrical housing 30. Pivotally attached to the arm 120 by means of a pin 122 is a link 124, as shown in FIGURE 1. Pivotally attached to the link 124 by means of a pin 126 is an arm 130. The end of the arm 130 is provided with an elongate slot 132 within which slidably moves a pin 134.

50 As shown in FIGURE 9, the pin 134 is secured to a bracket 136 which is axially movable upon one of the post members 115. The bracket 136 is connected to a similar bracket 138 by means of cross links 140. The bracket 138 is axially movable upon another of the posts 115. The cross links 140 support a connector 142 which retains the upper end portion of the main operating shaft 106. The connector 142 rotatably supports the main shaft 106 while preventing relative axial movement between the connector 142 and the main shaft 106. Thus, pivotal movement of the arm 130 causes axial movement 55 of the brackets 136 and 138 upon the post members 115, thus causing vertical movement of the main operating shaft 106.

60 As shown in FIGURE 1, intermediate the pin members 126 and 134 of the arm 130, a pin member 150 pivotally connects the arm 130 to a link 152. The link 152 extends through a slot 151 in a plate 153 and has a lower end portion 154 which is loosely encompassed by a collar 156. The collar 156 is attached to an axially movable shaft 159 which is provided with a rack 160 in meshed engagement with a pinion 162. The pinion 162

is connected to a rotatable shaft 164 of an adjustment motor or stepping motor 166. The stepping motor 166 is carried by a plate 167. Thus, it is understood that by rotary movement of the stepping motor 166, the pinion 162 is rotatively moved, causing axial movement of the rack 160. This causes lateral movement of the collar 156 and results in movement of the lower end portion 154 of the link 162. Movement of the link 162 causes adjustment of the arm 130 with respect to the pin 134.

The upper end portion of the link 162 is connected to a crank 165. As shown in FIGURES 1 and 14, the crank 165 is attached to a shaft 168 which supports a gear 169. The gear 169 is in meshed relation with a pinion 170 of a stepping motor or adjustment motor 172. A stepping motor 172 is carried by a plate 173. Thus, operation of the stepping motor 172 rotates the crank 165, adjusting the upper position of the link 162. Thus, it is understood that the stepping motors 172 and 166 adjust the length of stroke of the arm 130 as the arm 130 moves in response to movement of the arm 120. Thus, the stepping motors 172 and 166 adjust the length of reciprocal vertical movement of the main operating shaft 106.

Thus, it is also understood that as the main motor 40 causes rotation of the cam members 44 and 46, the main operating shaft 106 is caused to reciprocally move both axially and rotatively.

Attached to the lower portion of the shaft 106 is a winding head 180, which may be similar to that disclosed in my copending applications Serial Number 702,108 and Serial Number 19,692. A cylindrical cover member 181 encompasses a portion of the winding head 180. The winding head 180 is substantially cylindrical and has a plurality of parallel grooves or slots 182, as shown in FIGURE 2. There are the same number of slots or grooves 182 as the number of slots in an electrical element such as an element 184 which is wound by the winding head 180. Each groove 182 has a guide member 186 slidable therein, as shown in FIGURES 1, 2, and 10. The guide members 186 engage the teeth between the slots of the element 184 so that the guide members 186 remain with the element 184 during the winding operation, as shown in FIGURE 2. The electrical element 184 is retained by holder members 190 and 192. The holder members 190 and 192 are supported by brackets 194 which are carried by one of the leg members 24. Hook members 198 are pivotally supported in positions adjacent the ends of the element 184 during the winding thereof, as shown in FIGURES 1 and 2, and assist in proper forming of the ends of each of the coils formed during the winding process.

A plurality of nozzles 200 are attached to the main operating shaft 106 and are movable into and out of the slots of the electrical element 184 during the winding process. Ordinarily, the nozzles 200 are arranged in pairs. There may be two, four, eight, or other numbers of nozzles 200 so that a plurality of coils are simultaneously formed in the element 184 by the winding head 180. Wire members 202 extend downwardly through the upper end of the operating shaft 106 through flexible tubular conduits 204, as shown in FIGURES 1 and 9. The conduits 204 may be of plastic material and extend through the operating shaft 106 to the nozzles 200. During the winding operation, the nozzles 200 are carried axially through the slots of the electrical element 184 and when the nozzles 200 reach each end of the element 184 there is slight rotary movement of the shaft 106, rotating the nozzles 200. Thus, each nozzle 200 in forming each coil passes through one slot in one direction of stroke of the shaft 106 and through a different slot in the return direction of stroke of the shaft 106. Thus, the reciprocal rotary and axial movements of the main operating shaft 106 carry the nozzles 200 through the slots of the element 184 placing wires 202 in the slots of the element 184, forming the wires into coils. During the

winding process, each wire 202 moves inwardly through the upper end of the shaft 106 and is drawn downwardly by movement of the nozzles 200. In its downward movement each wire 202 passes through its respective flexible conduit 204 which is within the shaft 106. Each wire passes outwardly from its respective nozzle 200 and is formed into a coil as the nozzles 200 are moved by the shaft 106.

As shown in FIGURE 10, when it is desired to remove the element 184 after winding thereof, the holders 190 and 192 are lowered. The guide members 186 automatically move away from the element 184 as the guide members are carried by the winding head 180.

Any suitable wire cutting means 208 may be operated by means of a rod 210 to sever the wire members 202. The cutter members 208 may also be provided with means to grasp the wire members 202 so that the wires 202 extend from the grasping means during the winding operation, as shown in FIGURE 2.

Thus, it is understood that the apparatus of this invention provides means by which there is a definite relationship established between the reciprocal axial and rotary movements of the winding head 180 for precise forming of coils in an electrical element. Herein, the apparatus is shown for use in the winding of a stator. However, the apparatus is also adapted for use in the winding of rotors. Such operations are described in said copending applications Serial Number 702,108 and Serial Number 19,692. The apparatus of this invention may also be used for other winding operations. The relationship between and the amount of the reciprocal axial and rotary movements of the winding head 180 are adjustable by the adjustment motors 100, 166, and 172. The winding apparatus as disclosed herein may be automatically operated so that a very minimum amount of manual effort, if any, may be required.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. Winding apparatus comprising support structure, rotary motor means carried by the support structure, a pair of eccentric cam members fixedly attached to the motor means for rotation thereby, a pair of cam followers pivotally carried by the support structure, each of the cam followers being in engagement with one of the cam members for pivotal movement thereby, a first arm member, the first arm member being rigidly attached to one of the cam followers for movement therewith, linkage means pivotally connected to the first arm member and to the support structure so that the linkage means pivotally moves with movement of the first arm member, a reciprocally movable rotatable shaft member carried by the support structure, the linkage means being pivotally connected to the shaft member for axial movement of the shaft member, a second arm member, the second arm member being rigidly attached to the other of said cam followers for movement therewith, the shaft having a sprocket attached thereto for rotation therewith, a chain encompassing the sprocket and in mesh therewith, means connecting the second arm member to the chain for movement of the chain with movement of the second arm member so that the shaft member is rotatively moved with movement of the second arm member, and wire guide means attached to the shaft member.

2. Apparatus for winding an element of an electrical machine comprising support structure, rotary motor means carried by the support structure, first and second eccentric cam members attached to the rotary motor means for rotation thereby, a pair of annular cam follower mem-

bers, there being one cam follower member adjacent each of the cam members and in engagement therewith, each cam follower member having a portion pivotally attached to the support structure, a pair of arm members, there being a first arm member and a second arm member, each arm member being attached to one of the cam follower members at a portion thereof substantially opposite the portion thereof which is pivotally attached to the support structure, a linkage assembly pivotally attached to the first arm member and to the support structure, an axially movable rotatable shaft member carried by the support structure, the linkage assembly being pivotally attached to the shaft member for axial movement thereof, a sprocket wheel attached to the shaft for rotation therewith, an idler sprocket rotatably carried by the support structure, a chain encompassing the sprocket wheel and the idler sprocket and in meshed relation therewith, the second arm member extending to a position adjacent the chain, a slide support member rigidly carried by the support structure, a connector attached to the second arm member and slidably movable upon the slide support member, a yoke attached to the chain, the yoke having a portion slidable upon the slide support member on either side of the connector, spring means encompassing the slide support member and disposed between the connector and said portions of the yoke which slide upon the slide support member, an adjustable abutment member engageable by the yoke and limiting the movement thereof, and wire carrier means carried by the shaft member.

3. Oscillatory apparatus comprising a rotatably mounted shaft adapted to be rotated by suitable means, a sprocket wheel encompassing the shaft and attached thereto for rotation thereof, an idler sprocket spaced from the shaft, a chain in meshed relation with the sprocket wheel and the idler sprocket, a yoke having spaced-apart portions, spring means intermediate the spaced-apart portions of the yoke, and actuator means intermediate the spaced-apart portions of the yoke, the actuator means being reciprocally movable through a given distance, there being a portion of the spring means between the actuator means and each of said spaced-apart portions of the yoke, abutment means attached to the yoke for movement therewith, the yoke being reciprocally movable with movement of the actuator means as the actuator means applies forces upon the yoke through the spring means, and spaced-apart stop means engageable by the abutment means limiting reciprocal movement of the yoke as the actuator means reciprocally moves said given distance.

4. Winding apparatus comprising support structure, a rotary drive shaft, a pair of eccentric cam members carried by the drive shaft, a pair of cam follower members pivotally carried by the support structure, each of the cam follower members being in engagement with one of the cam members for movement thereby, each cam follower member being provided with an arm attached thereto at a position substantially opposite the pivotal attachment thereof to the support structure, a yoke slidably carried by the support structure, an elongate flexible member attached to the yoke for movement therewith, a rotatable and axially movable operating rod, connector means connecting the flexible member to the operating rod for rotative movement thereof, spring means connecting the yoke to one of the arms for movement of the yoke with movement of the arm, and means engageable by the yoke limiting movement thereof, linkage means pivotally connected to the other of said arms and pivotally connected to the operating rod for axial movement thereof, and wire carrier means carried by said operating rod.

5. Actuator mechanism comprising a rotary drive shaft adapted to be connected to suitable motor means for operation thereby, a pair of eccentric cam members attached to the drive shaft for rotation therewith, a pair of pivotal cam follower members, there being a first cam follower

5 member and a second cam follower member, there being one cam follower member in engagement with each of the cam members, a link pivotally attached to the first cam follower member, an arm pivotally attached to the link, a rotatable and axially movable shaft, the arm having an elongate slot therein, means extending through the slot and attached to the rotatable and axially movable shaft slidably and pivotally connecting the rotatable and axially movable shaft to the arm, a cross-link pivotally attached to the arm intermediate the ends thereof, adjustable connection means at each end of the cross-link adjustably positioning each end of the cross-link, an actuator arm rigidly attached to the second cam follower member, a flexible connector member, means connecting the flexible connector member to the rotatable and axially movable shaft for rotation thereof, a movable interconnection member attached to the flexible connector, adjustable abutment means engageable by the interconnection member limiting movement thereof, and resilient means connecting the actuator arm to the interconnection member so that the actuator arm moves a given distance upon each revolution of the drive shaft while the interconnection member and the flexible connector move a distance limited by the abutment means so that rotary movement of the rotatable and axially movable shaft is limited by the abutment means while the rotatable and axially movable shaft is rotated with movement of the actuator arm.

6. Actuator means comprising a pivotally reciprocally movable arm, the arm being adapted to be connected to means for movement thereof, a rotatable shaft, a flexible drive member encompassing a portion of the shaft, means connecting the flexible drive member to the shaft for rotation thereof, an interconnection member attached to the flexible drive member, the interconnection member being reciprocally movable along a substantially straight line, a rotary irregularly shaped abutment member having pairs of opposed surfaces engageable by the interconnection member limiting the reciprocal movement thereof, and resilient means connecting the pivotally reciprocally movable arm to the interconnection member for reciprocal movement of the interconnection member causing rotary reciprocal movement of the shaft.

7. Winding apparatus for an electrical element comprising:

a rotatable and axially movable shaft member, a pair of fixedly interconnected rotatable cam members, means for connecting the cam members to means for rotation thereof, a pair of pivotally movable cam follower members, there being a first cam follower member and a second cam follower member, there being one cam follower member in engagement with each of the cam members and movable thereby, rotary actuator means connected to the shaft member, connector means connecting the rotary actuator means to the first cam follower member for movement of the rotary actuator means with movement of the first cam follower member, the first cam follower member having a predetermined distance of movement, the connector means including:

a flexible member encompassing the shaft member, resiliently operable abutment means connected to the flexible member, and adjustable limit means engageable by the abutment means for limiting movement of the flexible member, the movement of the flexible member thus being adjustably limitable to distances less than the distance the movement of the first cam follower member, axial movement actuator means connected to the shaft member, and means connecting the axial movement actuator means to the second cam follower member.

8. Mechanism for winding an element of an electrical machine comprising:
 rotatable and axially movable carrier means,
 rotation means connected to the carrier means,
 axial movement means connected to the carrier means,
 first rotatable cam means,
 means for connecting said first cam means to means for rotation thereof,
 connector means connecting the first cam means to the rotation means for operation thereof, the first cam means having a predetermined distance of movement,
 the connector means including:
 a flexible member connected to the rotation means, engagement means attached to the flexible member, resilient means connecting the engagement means to the cam means,
 and abutment means engageable by the engagement means for limiting movement of the flexible means to distances less than the distance of movement of the first cam means,
 second rotatable cam means,
 means for connecting the second cam means to means for rotation thereof,
 the second cam means being connected to the axial movement means for operation thereof,
 and means securing the first and second cam means together for simultaneous operation.

9. Mechanism for precise reciprocal axial and rotary movement of a shaft comprising:
 rotary motor means,
 a pair of cam members attached to the motor means for rotation therewith, there being a first cam member and a second cam member,
 a pair of pivotally mounted cam followers, there being a first cam follower and a second cam follower, the first cam follower being in engagement with the first cam member for reciprocal movement thereby, linkage means pivotally connecting the first cam follower to said shaft for axial movement thereof, flexible means encompassing the shaft and operably connected thereto for rotation thereof, the second cam follower being in engagement with the second cam member for reciprocal movement thereby, means connecting the flexible means to the second cam follower for reciprocal movement thereby, rotatably adjustable abutment means, and engagement means attached to the flexible means,

the engagement means engaging the rotatably adjustable abutment means and limiting movement of the flexible means.

10. Operator apparatus including:
 a rotatable shaft adapted to be connected to means for rotation thereof,
 a wheel connected to the shaft for rotation thereof, a flexible member encompassing the wheel and extending therefrom and in engagement therewith, an engagement member attached to the flexible member and movable therewith, abutment means having adjustably positionable opposed abutment surfaces engageable by the engagement member, a yoke attached to the engagement member and movable therewith, the yoke having a midportion and a pair of spaced-apart end portions, the midportion of the yoke being movable with respect to the end portions thereof, resilient means intermediate the midportion and the end portions of the yoke so that said midportion is resiliently movable with respect to the end portions thereof,
 a reciprocally movable arm connected to the midportion of the yoke for movement thereof, the arm having a predetermined distance of reciprocal movement, the abutment means limiting movement of the engagement member and thus limiting movement of the flexible member, the midportion of the yoke thus being permitted by the resilient means to move farther than the end portions of the yoke, the amount of reciprocal rotational movement of the shaft thus being adjustably limited by the abutment means while the arm which moves the shaft has a predetermined fixed amount of reciprocal movement.
